Primary Examiner — Dominic Simone(74) *Attorney, Agent, or Firm* — Lane Powell PC(57) **CLAIM**

The ornamental design for a portion of a shoe upper, as shown and described.

DESCRIPTION

FIG. 1 is a front perspective view of a shoe upper showing my new design;

FIG. 2 is a medial side view thereof;

FIG. 3 is a front view thereof;

FIG. 4 is a rear view thereof; and,

FIG. 5 is a top view thereof.

The solid heavy line immediately adjacent to the shaded region forms the boundary of the claimed design. The remainder of the shoe is for environmental purposes only and forms no part of the claimed design.
